TABLE LAMP

Leo H. Klausen, 338 Hillcrest Ave., Willowdale,
Ontario, Canada

Filed Aug. 2, 1965, Ser. No. 86,404

Term of patent 14 years

(Cl. D48—20)

FIG. 1

FIG. 2

I claim:

The ornamental design for a table lamp, as shown and described.
